DESIGN FOR A BATTERY CONTAINER

Edwin J. Ward and Roy H. Griffiths, Akron, Ohio,
assignors to The B. F. Goodrich Company, New
York, N. Y., a corporation of New York

Application June 8, 1934, Serial No. 52,114

Term of patent 14 years

To all whom it may concern:

Be it known that we, EDWIN J. WARD and ROY H. GRIFFITHS, citizens of the United States, residing at Akron, in the county of Summit and State of Ohio, have invented a new, original, and ornamental Design for a Battery Container, of which the following is a specification, reference being had to the accompanying drawing, forming a part thereof.

The drawing shows a perspective view of a battery container embodying our design.

The side and the end of the container which are not in view in the drawing are the same in appearance as those that are in view.

We claim:

The ornamental design for a battery container as shown and described.

EDWIN J. WARD.
ROY H. GRIFFITHS.
